UNITED STATES PATENT OFFICE.

JAMES T. CLAWSON, OF IVANHOE, MINNESOTA.

CLOTHES-LINE.

1,252,240.

Specification of Letters Patent. Patented Jan. 1, 1918.

Application filed April 15, 1916. Serial No. 91,397.

To all whom it may concern:

Be it known that I, JAMES T. CLAWSON, a citizen of the United States, residing at Ivanhoe, in the county of Lincoln and State of Minnesota, have invented certain new and useful Improvements in Clothes-Lines, of which the following is a specification.

This invention relates to clothes-lines, and has more especial reference, to an improved support therefor.

The primary object of the invention, is to provide an adjustable support for clothes-lines, which may be either raised or lowered, in order that the article to be supported by the line, may be readily placed thereupon and also, when it is so desired, may be as readily removed therefrom.

Another important characteristic of the invention resides in the novel means employed for raising the line supporting member, consisting of a telescopic pole having a rack arranged upon one of its sections, and a pinion upon the other section whereby when said pinion is rotated through the application of suitable operating means thereto, one of the sections may be distended or telescoped and a locking member carried adjacent the pinion and engageable at times therewith which locking member will enable the person to maintain the pole in an adjusted position.

A still further object of the invention is to provide means in the form of horizontally arranged pulleys which are carried upon a suitable cross arm secured at a point adjacent the upper extremity of the movable section of the pole.

The invention also aims to provide a rotatable supporting bracket, whereby the user may deposit the receptacle containing the articles to be placed on the line thereupon.

I have illustrated the above-mentioned embodiments of the invention in the accompanying drawings forming a part thereof, and improved details in the construction and arrangement of parts will be apparent from an inspection of such drawings, in connection with the specific description hereinafter contained.

50. In the drawings:

Figure 1 is an elevation partly in section of my improved device;

Fig. 2 is a fragmental vertical section showing the construction of the telescoping parts and the operating means therefor;

Fig. 3 is a top plan of one of the cross bar sections which support the line pulleys;

Fig. 4 is a section taken on the line 4—4 of Fig. 1, looking in the direction of the arrows;

60

Fig. 5 is a fragmental section showing the manner in which the pulley supporting cross bars are connected with the movable section of the pole; and

Fig. 6 is a detail in perspective of one of the bracing elements for securing the pulley supporting cross bars to the movable section of the pole.

Referring now more particularly to the drawings wherein like reference characters 70 designate like or corresponding parts throughout the several views thereof, I provide a foundation or base as indicated by the numeral 1, this base being preferably constructed of cement. A hollow cylindrical 75 standard 2 has its lower extremity 3 embedded in the concrete base 1. A slot 4 is arranged in one side of the cylindrical element 2 and has arranged adjacent thereto, a bracket member comprising apertured ears 80 5 and 5', which ears are secured to the outer surface of said cylindrical element in any suitable manner as known to the art. A pinion 6 is mounted upon a shaft 7, the shaft in turn being supported in the alined 85 apertures formed in the ears 5 and 5' and has arranged thereupon an elongated extension 8, the outer extremity of this extension being adapted to receive a crank or other operating member 9. It is to be noted that a 90 portion of the pinion 6 projects through the slot 4 in the cylindrical standard 2 and engages a portion of a rack 10, which is formed upon one side of a movable pole 11. Rotation of the pinion 6, through the medium of 95 the crank 9 will cause the movable pole 11 to be raised or lowered, this depending upon the direction in which the pinion is rotated and, in order to provide means whereby the said movable pole 11 may be securely held 100 in an adjusted position, I provide a dog 12 which is pivoted to the ears 5 and 5' as at 13, the outer end of the dog being engageable with certain of the teeth of the pinion 6.

By this arrangement, it will be evident that 105 forward rotation of the pinion is permitted, yet reverse rotation thereof will be prevented, due to the engagement of the dog 12 with the teeth on the pinion 6.

In order to provide for means whereby a 110

plurality of pulleys may be supported, so as to permit the attaching of endless clothes lines thereabout, I secure to the upper extremity of the movable pole 11 a substantially U-shaped bracket 14, the rear wall of said bracket having formed thereupon an externally threaded shank 15 which extends through a suitable opening therefor in the pole and is held in position by means of a locking nut 15' which is turned into engagement therewith. Arranged within said U-shaped bracket and supported by the lower portions thereof is a cross arm 16, the rear edge of which is provided with a vertically disposed extension 17. A pulley 18 is then placed upon the upper face of the cross arm 16 and a complementary cross arm 19 having a similar extension formed upon its rear edge is adapted to engage with the vertical extension 17. Suitable openings are arranged in the laterally extended arms of the bracket 14 and also in the cross arms 16 and 19 and the pulley 18. These openings are brought into registration and a bolt 20 is passed therethrough, whereupon a locking nut 20' is turned into engagement with its threaded extremity so as to securely hold the various elements within the said bracket 14. It may be also stated that the extension as formed upon the rear edges of the cross bars 16 and 19 are formed by means of circular seats 21 which are arranged at intervals along the cross bars, as shown in Fig. 3, the forward ends of the circular seats 35 being cut away to produce flared mouth portions 22 for a purpose which will be subsequently apparent. Pulleys 23 and 24 are arranged upon either side of the pulley 18 and are received by the complementary seats 21 as arranged in the cross arms 16 and 19. These pulleys 23 and 24 are rotatable about shanks 25 which are formed upon the upper extremities of diagonally arranged bracing bars 26, and the pulleys are secured thereupon by means of locking nuts 27 which are turned into engagement with the threaded extremities of the shanks 25. The nuts 27 also serving as means for securing the diagonal bracing members 26 to the cross bars 16 and 19. The lower extremities of the diagonal bracing bars 26 have arranged thereupon offset portions 28, which portions are provided with interiorly threaded openings 28', whereby the same may be secured 55 to the sides of the movable pole 11 by means of screws or the like as at 29. A clothes line of the endless type, as indicated by the numeral 30 is applied to the pulleys 18, 23 and 24 and may be engaged at their forward ends with similar pulleys. If so desired, the user may employ a plurality of these telescopic supporting poles.

A supporting bracket 31 rotatably secured to the cylindrical standard 2 by means of 60 collars 32 and 32', which are loosely engaged

thereabout, is provided. The outer extremity of this supporting bracket may be circular as at 33 and receives thereupon a flared supporting member. This member 34 may be if so desired, formed upon the circular portion 33 or secured thereto in any suitable manner.

In reviewing the operation and assuming that the user desires to place various articles upon the line, the receptacle containing such articles is accordingly set upon the rotatable bracket 31. The locking dog 12 is then disengaged from the pinion 6 and the crank is turned in a reverse direction so as to permit the lowering or telescoping of the movable pole 11 within the cylindrical standard 2. When the desired adjustment has been obtained the locking dog 12 is released and will by gravitation again engage with one of the various teeth on the pinion 6. With the movable pole 11 thus adjusted the cross bars 16 and 19 carrying the clothes line will be brought into a position within reach of the user. The bracket 31 may be then swung into the desired position and the various articles may be removed from the receptacle as supported by said bracket, and attached to the line. As the various articles are attached, the line may, due to its endless arrangement be moved so as to carry the various articles as placed thereupon forwardly in order that other articles may be secured thereto. The crank 9 is then rotated in a forward direction, which movement will cause the pinion 6 to engage with the rack 10 and consequently again elevate the clothes line, the locking dog 12, serving as effective means for holding the same in its elevated position.

Still further embodiments of the invention than those especially defined, may be resorted to as conditions or preference may dictate as may be in keeping with the hereto appended claims.

I claim:—

1. A line support including a pole, a cross-bar secured to the upper end of the pole and having a plurality of spaced apart seats, a second cross-bar arranged to rest upon the first cross-bar and provided with complementary seats, pulleys rotatably mounted in the seats, and means for joining the bars.

2. A line support including a pole, a cross-bar comprising bar members having complementary spaced apart seats forming pulley recesses, a bracket mounted on the pole and secured to the cross-bar for supporting the cross-bar on the pole, pulleys rotatably mounted in the pulley recesses, and means for connecting the bars and providing journals for the pulleys.

3. A line support including a pole, a cross-bar comprising bar members having complementary spaced apart seats forming pulley recesses, a bracket mounted on the pole

and secured to the cross-bar for supporting the cross bar on the pole, pulleys rotatably mounted in the pulley recesses, a journal bolt for securing the bar members and providing the journals for one of the pulleys, and braces for the cross-bars, the lower ends of the braces being secured to the pole, the upper ends of the braces forming stub axles

for others of the pulleys and securing means for the bar members.

In testimony whereof I affix my signature in the presence of two witnesses.

JAMES T. CLAWSON.
